CLAIM

The ornamental design for a “full grip cookware top handle”, as shown and described.

DESCRIPTION

FIG. 1 is a perspective front view from above of the “full grip cookware top handle”, showing my new design;

FIG. 2 is top plan view thereof;

FIG. 3 is a front elevation view thereof;

FIG. 4 is a bottom plan view thereof; and,

FIG. 5 is a side elevation view.

The broken lines in FIGS. 1, 2, 4 and 5 are for illustrative purposes only, depicting the environment of the new design, forming no part thereof as claimed.
